UNITED STATES PATENT OFFICE.

CHARLES H. NUMAN, OF NEW YORK, N. Y., ASSIGNOR TO A. A. WEEKS-HOSKINS COMPANY, OF NEW YORK, N. Y., A CORPORATION OF NEW YORK.

DESIGN FOR AN INKSTAND.

No. 38,767.

Specification for Design.

Patented Aug. 27, 1907.

Application filed July 10, 1907. Serial No. 388,133. Term of patent 7 years.

To all whom it may concern:

Be it known that I, CHARLES H. NUMAN, a citizen of the United States, residing at New York city, in the county and State of New York, have invented a new, original, and ornamental Design for an Inkstand, of which the following is a specification, reference being had to the accompanying drawings, forming a part thereof, and in which— Figure 1 is a top view, Fig. 2 a front eleva-

tion and Fig. 3 an end view of an inkstand bearing and incorporating my design.

I claim:

The ornamental design for an inkstand, as shown.

CHARLES H. NUMAN.
